A. C. AXFORD

BASKET GRATE HEAT DEFLECTOR

Filed July 19, 1926

INVENTOR.

Allan C. Axford.

BY

Carlos P. Griffin
ATTORNEY.

UNITED STATES PATENT OFFICE.

ALLAN C. AXFORD, OF SAN FRANCISCO, CALIFORNIA.

BASKET-GRADE HEAT DEFLECTOR.

Application filed July 19, 1926. Serial No. 123,282.

This invention relates to an adjustable heat deflector for use with basket grates, and the invention is intended to provide means whereby the heat deflector may be adjusted 5 in position depending upon the draft of the flue under which the grate is installed to give much or little heat deflection as may be required.

Another object of the invention is to provide 10 means for the support of the heat deflector which may be cast integral with the grate itself, or it may be separately bolted thereto as may be desired in any particular instance.

15 Other objects of the invention will be apparent as the description proceeds.

An embodiment of the invention is shown 20 in the accompanying drawings in which the same reference numeral is applied to the same portion throughout the several figures of the drawings and of which there may be modifications.

Figure 1 is a front elevation of a grate with this deflector applied thereto,

25 Figure 2 is a view in end elevation of the grate with the deflector applied thereto, and

Figure 3 is a side elevation of one of the 30 detachable deflector supports which may be used on grates of any kind without special end castings.

The numerals 1 and 2 indicate the ends of the basket grate; 3 the back, and 4 the front, said grate being made in the usual manner and provided with legs 5, 6, 7 and 8.

35 At each back corner the grate is provided with an upwardly extending support as indicated at 9 and 10, and each of these supports is provided with an open curved slot as indicated at 11, and with a series of notches 40 12 on its upper edge, there being stops 13 and 14 on each standard to prevent the deflector from being pushed too far forward, or too far back.

The deflector consists of a plate 15 with 45 lugs 16 and 17 at its lower corners, and with shoulders 18 and 19 about the mid portion of each end to rest upon the notches 12 of the standards 9 and 10 to determine the inclination of adjustment of said deflector. The 50 deflector is placed in position by pushing its lugs 16 and 17 into the open slots 11.

If it is not desired to make up grates especially with this deflector, the deflector may be secured in place by use of the detachable 55 standard 20 at each upper corner of the grate, and it is secured to the grate 21 by

bolts 22, 23 extending through a depending lug 24 of said standard, and into specially threaded holes of the grate 21. This standard is slotted as indicated at 25 and has the 60 adjusting notches 26 with the stops 27—28 similar to the standard used with the other form of grate.

In practice the deflector is picked up with a poker by inserting it in the hole 15' enough 65 to lift it over the notches 12 and it is then either moved forward or back to a point which will give the desired heat deflection without causing smoke to be discharged into the room, the exact position being more or 70 less determined by the character of the draft produced in any given flue. That is, with a good flue the deflector can be pushed all the way forward, while with a poor flue it will 75 not be pushed forward so much.

Having thus described my invention, what I desire to secure by Letters Patent of the United States is as follows, but the construction may be modified in carrying out the invention as shown in the drawings and in the 80 above particularly described form thereof, within the purview of the annexed claims:

1. A device of the class described comprising the combination with a basket grate of a pair of standards carried thereby, 85 notches in the tops of each of said standards, pivot slots in each of said standards, a deflecting plate having shoulders adapted to engage said notches, lugs on said plate adapted to pivot and slide in said slots 90 whereby the angle of said plate may be adjusted by lifting it out of one pair of notches into another pair thereof.

2. A device of the class described comprising the combination with a basket grate 95 of a pair of standards secured to the back of said grate on each side thereof, a deflector plate pivotally mounted in slots in each of said standards, notches in the tops of each of said standards, shoulders on each side of 100 said plate adapted to engage said notches to permit the plate to be adjusted to several different inclinations with respect to the back of said grate.

3. A device of the class described comprising the combination with a basket grate of a detachable standard at each corner of 105 said basket, a plate pivotally supported in slots in said standards, notches in said standards adapted to be engaged by shoulders on 110 said plate to hold said plate at different angles.

4. A device of the class described comprising the combination with a basket grate of detachable standards carried thereby, said standards having a series of notches in their upper edge, a slot near its connection with the grate, a deflector plate having a pair of lugs extending into the slots of the standards and shoulders on said plate adapted to en-

gage said notches, whereby the deflecting plate may be raised to shift it from one inclination to another inclination as may be required. 10

In testimony whereof I have hereunto set my hand this 15th day of June A. D. 1926.

ALLAN C. AXFORD.
